UNITED STATES PATENT OFFICE.

HOLLEY CARTMILL, OF SPOKANE, WASHINGTON.

SPARK PLUG.

Application filed December 9, 1920. Serial No. 429,477.

To all whom it may concern:

Be it known that I, HOLLEY CARTMILL, a citizen of the United States, residing at Spokane, in Spokane County and State of Washington, have invented certain new and useful Improvements in Spark Plugs, of which the following is a specification.

The present invention relates to improvements in spark plugs for internal combustion engines, and contemplates a device of this character so constructed as to enable an inspector to ascertain the working conditions existing within the cylinder of the engine, and possessing features whereby the electrodes and adjacent parts of the plug within the cylinder are maintained free from accumulation of carbon, &c., thus providing for the dual purpose of a test plug and an electrode cleaner.

The primary object of the invention is the equipment of standard or other forms of spark plugs with means whereby a portion of the fuel mixture may be withdrawn from the interior of the cylinder, for inspection, and in so constructing this sampling means to form an auxiliary or delayed miniature explosion within the spark plug by means of which a continuous succession of blasts of gas is blown over the electrodes and adjoining parts of the plug, thus preventing accumulation of carbon and eliminating the undesirable conditions resulting from such accumulation.

With the above objects in view the invention consists in certain novel features of construction of the plug shell within the cylinder involving explosion pockets, and combinations and arrangements therewith of a testing plug, as will be hereinafter more fully pointed out and claimed.

In the accompanying drawings I have illustrated one complete example of the physical embodiment of my invention, combined and arranged with a standard form of spark plug, according to the best mode I have thus far devised for the practical application of the principles of my invention.

Figure 1 is a vertical central sectional view through a spark plug and the elements combined therewith forming the subject matter of my invention.

Figure 2 is a view in elevation of the spark plug, partly broken away for convenience of illustration.

Figure 3 is a bottom end view of the spark plug and connections.

In the preferred form of the invention as illustrated in the drawings I have utilized a standard form of porcelain spark plug 1, which, is provided with a metal thimble 2, 60 which latter is threaded as usual into the walls of the engine casing of an internal combustion engine, and the plug is locked in the shell or thimble by means of the lock nut or jam nut 3 of usual type. 65

At its lower end the metal thimble is provided with an inner cylindrical bore 4 into which the tapered end of the plug, as 5 projects, and the stem or rod 6 of the plug which extends through the plug from end 70 to end is provided with the usual binding nuts 7 for the wire terminals of the sparking circuit, not shown. The electrodes 8 and 9 at the lower end of the stem 6 form the spark plug points for the spark gap or 75 ignition medium and these elements, as shown in Figures 1 and 2 are located below the thimble or shell to project the required distance in the engine cylinder for igniting the fuel charge therein. 80

The lower end of the shell, or that portion within the engine cylinder is of special formation, and is equipped with a pair of pockets or chambers 10, each having a restricted opening or mouth 11. The mouths 85 open through the lower edge of the wall of the shell and the pockets or chambers extend upwardly in the wall of the shell, increasing in area from the restricted mouth as best seen in Figure 2. The two chambers are located in diametrically opposite positions at the sides of the electrode of the spark plug, and as seen in Figure 3, these chambers are annular spaces extending circumferentially around the shell wall with 95 the walls of the chambers diverging from the opposed ends of the openings or mouths 11, thus materially increasing the interior area of the chambers, as they approach their upper or inner closed ends. 100

At or near the inner ends of the chambers 10, the shell is transversely bored, from the outside to form a threaded socket 12, 12, one at each side of the shell and each opening into a chamber or pocket 10. 105 Either one of these duplex sockets may be utilized as required, the one not being used having a threaded closure or plug 13 to close the upper or inner end of the chamber to which the socket leads. 110

In Figure 1 the right hand socket or threaded bore 12 has secured thereto a test

cock 14, provided with a fiber handle 15 and an elbow or pipe bend 16, the latter threaded into the socket and opening into the inner end of the pocket or chamber 10 at the right 5 of the shell in Figure 1, and thus establishing communication between the interior of the cylinder and the cock.

By turning the handle 15 of the cock a portion of the gas from the cylinder may 10 be permitted to pass therethrough to the atmosphere, and the gas or vapor emitted from the cock is subjected to inspection. By this inspection the quality of the fuel mixture within the cylinder may be ascertained, and if necessary the mixture may be 15 changed to rectify undesired conditions and increase the explosive effect of ignition. The compression of the mixture may also be determined by the velocity of the gas 20 escaping through the test cock, and other conditions existing within the cylinder may also be ascertained, as for instance whether the spark is weak or strong, and with this knowledge proper action may be taken to 25 correct, change, or rectify the existing conditions to enhance the efficiency of the engine.

The function of the auxiliary chambers 10 is to create a delayed, miniature, explosion 30 of fuel gas to provide a blast of gas past the electrodes and the lower end of the spark plug thus preventing accumulation of carbon at this point. Upon the compression stroke of the piston, a charge of gas is forced 35 through the restricted mouths of the chambers 10, with the result that when the charge in the cylinder is ignited the explosion is conveyed or transmitted to the interior of these chambers and a delayed explosion 40 occurs in these chambers. The blast from the explosions within the chambers results in a rush of gases through the restricted mouths of the chambers, directed toward the cylinder and past the electrodes and 45 adjacent parts of the spark plug and shell. These blasts of gas prevent accumulation or

lodging of carbon on the electrodes, thus maintaining them in a clean condition best adapted for efficient sparking. The scavenging stroke of the piston, by suction, withdraws and expels the burnt gases from the chambers, the fresh fuel is supplied to the chambers simultaneously with the charge to the cylinder. 50

By means of the test cock gas may be 55 taken from the cylinder of the engine in the immediate vicinity of the electrodes or spark plug points 8 and 9, for testing, as for example, if the cylinder is firing properly, when the test cock is opened a puff of 60 gas will be forced out on the compression stroke of the piston up through the chamber 10 and thence through the test cock 14, and the noise of the puff will be audible. When the ignition and explosion take place 65 in the cylinder a second blast or puff will occur, if all is well; if the second blast does not occur, it will be apparent that the cylinder is not firing, and when the different cylinders of the engine are tested separately 70 the location of the trouble may quickly be determined. The test cock must not be opened too wide, as the inrush of air, due to suction at the time of the suction stroke of the piston, may cause the mixture of gas about the 75 spark plug to be too lean with consequent misfiring.

Having thus fully described my invention, what I claim as new and desire to secure by Letters Patent is—

The combination with a spark plug and its attaching shell formed with an inner bore surrounding the sparking end of the plug, said shell having a chamber in its wall formed with a restricted mouth opening 80 into the engine cylinder and adapted to receive an explosive mixture whereby a blast of gas occurs past the sparking end of the plug with an explosion in said chamber. 85

In testimony whereof I affix my signature. 90

HOLLEY CARTMILL.
